MIXER FOR PETROLEUM OIL REFINING

Cyril L. Erickson, Whiting, Ind., assignor to
Standard Oil Company, Chicago, Ill., a cor-
poration of Indiana

Application September 18, 1930
Serial No. 482,695

6 Claims. (Cl. 196—46)

This invention pertains to orifice mixers which may be used for various purposes and more particularly to a mixing device suitable for effecting a thorough and homogeneous mixing, contacting or intermingling of immiscible materials, at least one of which is in a fluid state. The improved mixing device may be very advantageously used in petroleum refining operations as in cases where it is necessary to treat oil with relatively small amounts of non-miscible reagents such as sulfuric acid, water, alkali, sodium plumbite solution and the like.

In my prior Patent #1,698,432, dated January 8, 1929, I have described an analogous device useful for the same purposes to which the instant device may be put. This prior device is somewhat expensive to manufacture and has other disadvantages, although it is very useful for its purposes. One of the primary objects 20 of the present invention is to provide a mixer which will be very simple in construction and operation and which may be manufactured at a reasonably small cost.

Another object is to provide a mixer so constructed and arranged that it may readily be taken apart, cleaned, repaired and replaced with the greatest facility. In the connection the mixer in its preferred form is made in a plurality of interchangeable, readily removable sections adapted to be placed in an ordinary pipe line or the like.

Still another object is to provide a mixer in which the treating material may be introduced substantially into the center of the stream of material that is to be treated.

Many further objects, including the provision of means for determining the pressure in any section or portion and the differential pressure between sections or portions, will be or should 40 become clearly apparent and understood after reading the following description and claims and after viewing the drawing in which:

Fig. 1 is a longitudinal sectional view through a preferred form of mixing device constructed 45 in accordance with the invention.

Fig. 2 is a developed plan of one of the perforated cone elements used in the mixer.

Fig. 3 is a view similar to Fig. 1 of a modified form of mixing device, and

Fig. 4 is a plan view of one of the swirl producing elements used in the modified form shown in Fig. 3.

Referring first to Figs. 1 and 2, the mixer therein illustrated is adapted to be coupled in 55 a pipe line leading to a settling tank or other

place of disposal and comprises a section 2 which may be a part of the pipe line proper, and three substantially identical and interchangeable sections 3, 4 and 5. The flow of fluid to be treated is indicated by the large arrow, that is, from section 2 to section 5. A jet or pipe 6 projects radially through an opening in the wall of section 2 just ahead of the section 3 and opens at 7 somewhat against the flow of material to be treated but substantially 60 at the center of the stream. The treating material may be forced under pressure through the pipe 6 and out of the orifice 7 into the flowing stream of material passing there-through.

Each of the sections 2, 3, 4 and 5 may be connected to its adjacent sections by means of flanges 8 together with bolts or the like or may be otherwise suitably connected, as will be appreciated. Each of the sections 3, 4 and 5 may be formed from an ordinary piece of pipe of 70 proper strength and dimensions but preferably of steel or similar material which may be welded. Within each of the sections 3, 4 and 5, a substantially cone shaped foraminous element 9 is disposed with its axis substantially coincident 75 with the axis of the section and is held therein in fixed position in any suitable manner although, because of simplicity of construction, welding, as indicated at 11, is preferred. The conical mixing elements may be made of sheet 80 metal, as illustrated in Fig. 2. As shown in this figure, the element may be a sheet metal stamping provided with a reasonable number of openings 12 through which the materials to be mixed are forced to pass. The number of apertures 85 and their size, arrangement, form, and location may vary depending upon the materials to be treated, upon the pressures and other features which should be well understood by those skilled in the art. After the cone has been punched 90 out it is formed around into cone shape and its edges welded or otherwise secured together. A central cap 13, which may be perforated or imperforate, is welded, soldered or otherwise connected to the walls of the cone.

In order to determine the pressure in any section of the mixer and the differential pressure as between sections, each section (3, 4 and 5) may be provided with a short length of small piping or tubing 14 adapted to be connected into a 105 manifold pipe or tube 15 to the center of which a connection 16 for a pressure gauge is coupled. A valve 17 may be placed in the manifold between the section 3 and the connection 16 and likewise a valve 18 may be placed in the mani- 110

fold between the section 5 and the connection 16, while a valve 19 may be placed between the gauge or connection 16 and the section 4. A valve 21 may be put in the line between the connection 16 and the manifold. Should it be desired to obtain the pressure in any section, the valves to the other sections will be closed and the valve to the particular section will be open. In this way pressure and other conditions may be determined easily. Should the orifice of the mixer become obstructed with material too coarse to pass through them, the condition can be detected by means of the abnormally high pressure drop across the cone. With this information, the operator can remove the obstructed cone for cleaning by means of the flanges, 8, without dismantling the entire mixer. In a continuous operation, two mixers may be connected in parallel to be used alternately while one is being cleaned.

In the modified form shown in Fig. 3, the cone mixing elements 22 and 23 are constructed in the same manner as the cones 9 previously described but are differently arranged and differently spaced from the previously described form of mixer. Intermediate the mixing elements 22 and 23 are a plurality (in this case four) of stationary blade vane mixers designated 24, each of which has four blades, as better illustrated in Fig. 4. These vanes are welded around their rims to the interior wall of the pipe 25 and arranged therein in any suitable manner and spacing to provide a swirling action.

In operation of the materials which may, for instance, be oil and sulfuric acid, are supplied through the section 2 and the pipe 6 respectively, the treating material in this case, sulfuric acid, a fluid being injected into the center of the stream of oil. This starts the mixing which continues as the two fluids pass on through the perforated cones or screens 9 through the several sections 3, 4 and 5, so that a homogeneous and intimate mixing and contacting between the particles of each liquid is obtained. The liquids passing through each opening in each cone, jet into the body of mixture between cones and thereby cause a very thorough mixing and contacting action. If desired, any greater or lesser number of cones or sections may be used and it is a very simple matter with the construction illustrated to remove and replace any section for cleaning or repair or replacement. Furthermore should it happen that three mixing sections are found insufficient to give the required mixing or contacting, it is a very easy matter to add additional sections.

I have found that a plurality of orifice plates succeeding one another provides much more perfect mixing than one plate, regardless of its efficiency. This is due to the fact that where two immiscible liquids are brought together, they tend to stratify and pass through separate sections of the orifice plates. The incomplete mixture formed by the first plate can then be thoroughly disintegrated by the succeeding plates. For this reason I sometimes prefer to employ larger orifice holes in the first plate whose function is principally to produce a coarse dispersion, making the succeeding plates with increasingly smaller and/or fewer holes to provide higher orifice velocities. Thus I effect an economy in the operation of the mixer by reducing the pressure drop on the first plate, the efficiency of which will generally be low anyway.

In this case the sections will not be strictly interchangeable.

The mixer illustrated in Figs. 3 and 4 operates in a manner very similar to the manner of operation of the mixer previously described, although it may not be, under some conditions and circumstances, quite as efficient as a mixer utilizing three or more cones. The vanes 24 cause the fluids to swirl about in a helical path as they flow through between the cones and together with the cones provide a homogeneous and thorough intermingling of the treating material with the material being treated.

While I have illustrated and described two forms of my invention, it should be understood that it is susceptible of many other modifications and arrangements without departing from the spirit of the invention or the scope of the appended claims.

I claim:

1. A mixer for petroleum oil refining comprising, a plurality of relatively short lengths of pipe, means for detachably connecting said lengths together in fluid-tight relation, a sheet metal element of cone shape secured in each length of pipe and coincident with the axes of said pipes, said sheet metal elements having a plurality of spaced openings through the walls thereof, a plurality of small pipes, one small pipe opening into each of said pipe lengths, a small pipe providing a manifold and connected with each of the small pipes opening into said pipe lengths, a pressure gauge connection on said manifold, and a valve between each pipe length and said pressure gauge connection.

2. A mixer for petroleum oil refining comprising, a plurality of relatively short tubular members, means for detachably connecting said tubular members together in fluid-tight relation, a foraminous member disposed in each of said tubular members with the axes of said foraminous members substantially coincident with the axes of said tubular members, a plurality of small conduits, one small conduit opening into each of said tubular members, a small conduit providing a manifold and connected with each of the small conduits opening into said tubular members, a pressure gauge connection on said manifold, and a cut-off means between each tubular member and said pressure gauge connection.

3. A mixer for petroleum oil refining comprising, a plurality of tubular members, connecting means on the end of said tubular members, a foraminous member disposed at each end of one of said tubular members with the axes of said foraminous member substantially coincident with the axis of the tubular member, a conduit connected to said tubular member at places upstream and downstream with respect to the foraminous members for determining the pressure drop between said places, and means for introducing a fluid into the center of one of the tubular members.

4. A mixer for petroleum oil refining comprising, a plurality of tubular members, connecting means on the end of said tubular members, a foraminous member disposed at each end of one of said tubular members with the axes of said foraminous members substantially coincident with the axis of the tubular member, a vane disposed between said foraminous members, a conduit connected to said tubular member at places upstream and downstream with respect to the foraminous members for determining the pres-

sure drop between said places, and means for introducing a fluid into the center of one of said tubular members.

5. An apparatus for mixing petroleum materials of the character described comprising; means for introducing one material into the center of a flowing stream of a second material; a tubular pipe member for receiving the flowing materials; a hollow, frusto-conical member having a plurality of openings in the walls thereof disposed in said pipe member and secured by the rim of its base to said pipe member; and the end of said frusto-conical member being imperforate and a mixing vane disposed across the tubular pipe member adjacent the frusto-conical member.

6. A fluid mixer for petroleum liquids comprising a plurality of independent tubular mem-

bers, means for detachably connecting said members together in fluid tight relation, a hollow cone-shaped member having a plurality of openings through the conical walls thereof disposed and secured in each of said tubular members, the axes of said cones being substantially coincident with the axes of the respective tubular members, means disposed up-stream with respect to at least one of the conical members for introducing material into the center of a flowing stream of a second material, and means connected to and between two of said tubular members at places up-stream and down-stream with respect to at least one of said conical members for determining the pressure drop between said places.
